UNITED STATES PATENT OFFICE.

WILLIAM H. BALDWIN AND CHARLES T. PLUMMER, OF DULUTH, MINNESOTA.

SNARE DRUM.

Application filed February 27, 1922. Serial No. 539,695.

To all whom it may concern:

Be it known that we, WILLIAM H. BALDWIN and CHARLES T. PLUMMER, citizens of the United States of America, and residents, respectively, of Duluth, county of St. Louis, and State of Minnesota, have invented certain new and useful Improvement in Snare Drums, of which the following is a full and clear specification:

10 The object of this invention is not only to provide simple means for tightening the snares individually so that they may all be tensioned alike, but also to enable the snares to be released in a body when it is desired 15 to muffle the drum, as more fully herein-after set forth.

In the drawing—

Fig. 1 is a partial sectional and perspective view showing the form of our application which we prefer;

Fig. 2 is a detail cross-section through crosshead 12 and its support;

Fig. 3 is a face view showing the detail of member used for individual snares adjustment;

Fig. 4 is a cross-section on line 4—4 of Fig. 3, showing the application of the snares holder to the drum.

Referring to the drawing annexed by reference-characters, 5 designates the head of the drum, 6 the usual cylindrical body of the drum, 7 the usual bead at the end of the cylindrical body, around which bead the snares 8 are bent. At one end, the snares are attached to a plate 9 which, midway its length, is provided with a threaded opening to enable it to have threaded engagement with a depending screw 10 having a milled thumb-head 11 at its upper end, this milled head 30 resting upon a cross-head 12 whose cylindrical ends 13 have bearings in a pair of brackets 14 rigidly projecting from the side of the drum. By operating the screw 10 through the thumb-piece 11, it will be seen that the 35 snares may be tensioned as a whole, and, in order that the snares may be released as a whole, the bearing-pins 13 of the cross-head 12 are specially mounted in the brackets 14. The brackets are provided with arcuate slots 40 45 which extend downwardly and outwardly and are abruptly turned inwardly at their upper ends to provide upwardly-facing shoulders 16 and also inwardly at their lower ends to provide outwardly-and-downwardly-facing shoulders 17. With this construction, it will be observed that when the

pins 13 are at the upper ends of the slots, they will rest upon the upwardly-and-outwardly-facing shoulders 16 and thus be supported and held down against said shoulders 60 by the tension on the snares. When, however, it is desired to release the snares to muffle the drum, the cross-head 12 is thrown out into the main parts of the slots, whereupon the tension on the snares pulls the 65 cross-head downwardly until the pins 13 rest in the lower ends of the slots, being pulled inwardly against the shoulders 17 by the tension on the snares. When the snares are again to be tightened, the cross-head may 70 be readily pulled up in the slots until the pins 13 again rest on the shoulders 16. In this way, we provide a very simple and quick method of releasing and tightening the snares as a whole. It will be observed that 75 the cross-head 12 is provided with shoulders 18 which are adapted to contact with the inner faces of the brackets 14 to thus keep the cross-head centrally positioned.

At the opposite side of the drum, we provide a special arrangement for anchoring the individual snares in order that they may each be tensioned independently of all the other snares. As a convenient way of doing this, we provide a block 19 rigidly fastened 80 to the exterior of the main wall of the drum and provide said block with two rows of vertical holes, the holes of one row being staggered with reference to the holes in the other row. Up through these holes, the individual 90 snares are inserted, and each is held in its adjusted position by means of an individual set-screw 20 tapped into the outer face of the block 19, the set-screws being also arranged in two rows, one above the other, the 95 set-screws of one row being staggered with reference to the screws in the other row. With this construction, each individual snares may be pulled to the desired tension, this being done by hand, and, when the desired tension is obtained, it may be made permanent by tightening the set-screw. It often happens that certain individual snares, being a little loose, will "sing" and thus interfere with the pure tones of the drum; 100 with our device, each snares may be independently adjusted without reference to the tension of any other snares, and consequently we are able to maintain at all times the entire series of snares in proper condition 110 to produce the purest tones.

The snares may be connected to the com-

men cross-bars 9 in any suitable manner, but we prefer to provide the cross-bars with two rows of holes and thread the snares through the holes in pairs, so that loops 21 formed in the snares will lie on the upper side of the bar. The bends in the snares formed by these loops are too abrupt to permit the snares to slide through the holes in the bar during individual tensioning of the 10 snares at the other side of the drum, so that the tensioning of one snare will not in the least affect the tensioning of the connected adjacent snare.

We do not desire to be understood as limiting ourselves to the precise details of construction and arrangement shown, as variations and modifications therefrom may be made without departing from the spirit and scope of our invention and improvements.

We therefore reserve the right to all such variations and modifications as properly fall within the scope of our invention and improvements and the terms of the following claims.

25 What we claim is:

1. In a snare drum, means at one side of the drum for releasing the snares in a body, and means at the other side of the drum whereby the snares may be individually tensioned, said latter means consisting of a 30 perforated block affixed to the drum and provided with a set-screw for each perforation, each perforation being adapted to receive one of the snares, said perforations being arranged in two rows, the perforations in one row being staggered with reference to the perforations in the other row.

2. In a snare drum having a body and snares, means for supporting the snares, 40 means for tensioning as well as releasing the snares in the body, embodying a bar con-

nected to all the snares, a screw for adjusting said bar, a cross-head supporting said screw, and brackets supporting said cross-head, said brackets having each an arcuate 45 slot extending downwardly and outwardly, the ends of the cross-head being engaged in these slots.

3. In a snare drum having a body and snares, means for supporting the snares, 50 means for tensioning as well as releasing the snares in a body, embodying a bar connected to all the snares, a screw for adjusting said bar, a cross-head supporting said screw, and brackets supporting said cross-head, said 55 brackets having each an arcuate slot extending downwardly and outwardly, and adapted to slidingly hold the ends of said cross-head, each of said slots having an upwardly-facing shoulder at its upper end upon which the ends of the cross-head are adapted to rest.

4. In a snare drum having a body and snares, means for supporting the snares, means for tensioning as well as releasing the 65 snares in a body, embodying a bar connected to all the snares, a screw for adjusting said bar, a cross-head supporting said screw, and brackets supporting said cross-head, said 70 brackets having each an arcuate slot extending downwardly and outwardly, and adapted to slidingly hold the ends of said cross-head, each of said slots being provided with an upwardly-facing shoulder at its upper end and also with an outwardly-and-downwardly-facing shoulder at its lower end.

In testimony whereof we hereunto affix our signatures this 20th day of February, 1922.

WILLIAM H. BALDWIN.
CHARLES T. PLUMMER.
